JEWEL SETTING

Philip Colmar, Forest Hills, N. Y.

Application February 27, 1953, Serial No. 23,827

Term of patent 14 years

(Cl. D45—1)

To all whom it may concern:

Be it known that I, Philip Colmar, a citizen of the United States of America, residing at Forest Hills, in the county of Queens and State of New York, have invented a new, original, and ornamental Design for a Jewel Setting, of which the following is a specification, reference being had to the accompanying drawing, forming part thereof.

Fig. 1 is a top plan view of a jewel setting showing my new design;

Fig. 2 is a sectional view thereof taken along the lines 2—2 of Fig. 1;

Fig. 3 is a side elevational view thereof; and

Fig. 4 is a front elevational view thereof.

The dominant features of my design reside in the jewel setting shown in full lines.

I claim:

The ornamental design for a jewel setting, substantially as shown and described.
